UNITED STATES PATENT OFFICE

MARGARET LINDALE DUGDALE, OF BALTIMORE, MARYLAND, ASSIGNOR TO MARYLAND
GLASS CORPORATION, OF BALTIMORE, MARYLAND, A CORPORATION OF MARYLAND

DESIGN FOR A VASE

Application filed April 1, 1931. Serial No. 39,328. Term of patent 3½ years.

To all whom it may concern:

Be it known that I, MARGARET LINDALE DUGDALE, a citizen of the United States, residing at Baltimore, in the State of Maryland, have invented a new, original, and ornamental Design for Vases, of which the following is a specification, reference being had to the accompanying drawings, forming part thereof.

Fig. 2 is a top plan view thereof.

I claim:

The ornamental design for a vase, as shown.

MARGARET LINDALE DUGDALE.
